(57) **CLAIM**

The ornamental design for an identification tag for tubular and rolled materials, as shown and described.

DESCRIPTION

FIG. 1 is a top, front and right side perspective view of an identification tag for tubular and rolled materials showing my new design;

FIG. 2 is a front elevational view thereof;

FIG. 3 is a right side elevational view thereof, the left side elevational, top plan and bottom plan views all being a mirror of that shown; and,

FIG. 4 is a rear elevational view thereof.

1 Claim, 1 Drawing Sheet

FIG. 2

FIG. 3

FIG. 1

FIG. 4
